United States Patent Office.

JAMES M. WILLIAMS, OF CONNERSVILLE, INDIANA.

Letters Patent No. 61,592, dated January 29, 1867.

IMPROVEMENT IN BLOWERS.

The Schedule referred to in these Letters Patent and making part of the same.

TO ALL WHOM IT MAY CONCERN:

Be it known that I, JAMES M. WILLIAMS, of Connersville, in Fayette county, Indiana, have invented a new and useful Improvement in Rotary Blowers; and I do hereby declare that the following is a full and exact description thereof, reference being had to the accompanying drawings and to the letters of reference marked thereon.

Figure 1 represents the end of my rotary blower, with the two pinions on the projecting ends of the shafts.

Figure 2 is a vertical cross-section of the blower and its case, with the openings in the latter, and the angular deflector.

In the accompanying drawings, A indicates the case, and B B are the fans. Each of the fans is provided with a shaft C, journaled in the heads or ends of the case A, and are provided with pinions meshing together at one or both ends of the case, and exterior thereto. The fans consist of three vanes each, which vanes are cylindrical at their extremities, forming a semicircle; and between the three vanes there is a semicircular depression corresponding in size and form with the vanes b b b. The case A is closed except the apertures for the ingress and egress of the air. In fig. 2, the two fans, or sets of vanes, are represented within the blower-case, and are so arranged as to work in close proximity as they revolve in the direction indicated by the arrows. The case forms a half cylinder, from a vertical plane through each of the fan shafts. A portion of each end of the case near its bottom is left open for the free admission of the air, and an angular deflecting board is arranged centrally under the blower. The object of this deflecting board d is to deflect the current of air generated by the vanes b b b, as they move together downwardly through the centre of the case A. The edges of the deflecting board extend towards and may be made to pass within the casing, but there must be a slot for the admission of the air between them. The egress pipe f is placed centrally at the top of the case. The blower may be driven by a pulley on the end of one of the projecting fan shafts.

The operation of my improved blower is as follows: Power being applied to the fan shaft, the fans revolve outwardly from the bottom of the case, and enclose a body of air by the action of each vane, between the vanes and the casing, carrying it around to the egress pipe, where the vane meshes like the cogs of a pinion into the semicircular space between them; and as they continue to revolve the vanes move downwards in the arc of a circle through the centre of the case, when they each move outwardly to gather and carry forward another body of air to be discharged at the egress pipe f. The use of six vanes in a case, in the manner of my invention, causes a continuous regular blast of air to be ejected from the egress pipe; whereas a less number of vanes will cause an irregular and intermittent blast. Another advantage of the use of the three-vaned fans is in the trough-shaped spaces between the vanes, which serve as retainers of air, as they have a capacity to gather and retain the air, which effect cannot be attained by a less number of vanes on a single shaft. The deflecting board d, of angular form, serves to deflect the current of air generated by the downward movement of the vanes, and causes it to be directed into the space between any two of the vanes and the casing, as the vanes begin their ascent from the bottom of the case.

Having now fully described my improvement in blowers, what I claim and desire to secure by Letters Patent, is—

The construction of the three-vaned fans B B, used in combination with the semi-cylindrical case A, having openings at the ends for the admission of air; and the deflecting board d, arranged so as to leave a slot for the admission of air between it and the case A, operating in the manner and for the purpose specified.

In testimony whereof I have hereunto set my hand this 18th day of May, 1866.

J. M. WILLIAMS.
